(57) CLAIM

The ornamental design for a tobacco taster, as shown and described.

DESCRIPTION

The article embodying the design is intended to be used as a device for the one-time tasting of tobacco.

FIG. 1 is a perspective view of the tobacco taster of this invention;

FIG. 2 is a bottom view of the tobacco taster;

FIG. 3 is a top view of the tobacco taster;

FIG. 4 is a front view of the tobacco taster, the back view being a mirror image thereof; and,

FIG. 5 is a cross-sectional view of the tobacco taster taken on lines 5—5 of FIG. 3.
